MOVING-PICTURE-DISPLAY SCREEN.

1,356,659.

Specification of Letters Patent. Patented Oct. 26, 1920.

Application filed November 21, 1918. Serial No. 263,619.

To all whom it may concern:

Be it known that we, FREDERICK C. ROCKWELL, of Hartford, in the county of Hartford and State of Connecticut, and WILBUR M. DAVIS, of Gloucester, in the county of Essex and State of Massachusetts, citizens of the United States, have invented a new and useful Improvement in Moving-Picture-Display Screens, of which the following is a full, clear, and exact description.

The object of our invention is a display screen for moving pictures that will tend to display the projected photographs in pleasingly-colored and apparently-natural tints and at the same time give relief from eye-strain by the extreme softness and delicacy of their coloring.

It is the further and even more essential object of our invention to provide a display screen universal in character in the sense that it will possess the advantages above described when pictures from any style or subject of film are projected upon it.

A display screen embodying our invention can best be appreciated and understood from a consideration of the various elements entering into its production as we have found by our experiments. Before referring to these elements, we would point out that while we have found that a universal screen, in accordance with the objects of our invention, can be obtained through a color effect applied to the screen either by painting thereon or by projection, the mere coloring of a screen in various parts to satisfy the conditions of a picture projected from a single film is entirely inadequate and inefficient for any other conditions than those for which it was initially made. In other words, to provide a screen universal in character, which will satisfy any condition, a color scheme or effect had to be obtained of a distinctive and arbitrary character.

The invention can be better explained in the light of the drawing in which there is shown in front elevation a screen illustrative of the manner in which the patches of color are distributed over the screen. In other words, the face of the screen has been treated with a color scheme or arrangement of colors substantially in accordance with the principles illustrative of the invention. The various colors are numbered 1 to 5, inclusive,

and of these 1 represents blue, 2 pink, 3 yellow, 4 purple and 5 green.

Referring now to the various elements entering into our screen, there may be enumerated the following:

The application to the screen of a color scheme or effect comprising a number or variety of intermingled colors of weak tone density, blended together along their meeting edges so as to efface the line of demarcation between the same. In this connection the drawing is hardly illustrative of the manner in which the colors are blended together along their meeting edges, this being difficult of illustration but being an expedient well known to those skilled in the art.

The density of the colors should be so weak that the colors will appear upon the screen as mere tints, each tint retaining its own individuality except along the meeting edge of the various tints where the blending takes place. In fact, every color or tint should be weaker in tone density than the middle tones of the average picture when projected upon the screen. This keeps the coloring on the screen at all times subordinate to the design of the picture, whereas if strong colors were used on the screen with a weak projected picture, one would see more pronounced the predominating colors, while the picture and its details would be faint and more or less lost, the effect being one of incongruity. Moreover, if the colors were equally as strong as the projected picture, they would have to be suitable and conform with the design of the picture, therefore register with it, and would not do for any and every subject.

To obtain the best effects, all the colors including the blending should have substantially the same tone density. In this connection it should be noted that great care should be exercised that the blending be of such delicate application as not to appear of a stronger tone density than the colors between which the blending is effected.

While the tone density of the colors should be weak as above described, yet brilliancy is desirable, those colors being preferably employed that will impart brilliancy even when their density is weak, such as the colors presently to be referred to.

The general scheme and arrangement ap-

plied to the screen should be, also, of a sectional character, taking into consideration that portion of the screen where the animation of movement of objects and human beings is most likely to occur in the general run of films and as distinguished from those portions of the screen which display inanimate objects or effects. This is essentially a matter of estimation, it being found that 5 the action or movement of people or objects generally takes place between and removed from the top and bottom of the screen. For instance, on a screen whose picture was 14 feet from top to bottom, the average amount 10 of action would occur approximately in an area between 24 inches removed from the top of the screen and 18 inches from the bottom. The preferred arrangement is, as 15 follows:
 20 There is applied to that portion or section of the screen where the most action takes place a suitable color scheme and arrangement of colors, which takes also into consideration the general movement or direction 25 of movement of persons or objects appearing on the screen. In providing a suitable color scheme and arrangement of colors for that portion of the screen where the most action takes place, we found that the 30 color scheme and arrangement which gave the best results was one in which a variety of soft colors was employed running across the screen for long or short distances as distinguished from up and down the screen 35 and with the edges carefully blended, the colors practically running into each other. The colors preferably employed for this portion of the screen are pink, orange and purple and, as we have found that moving 40 objects, persons and animals when displayed with these colors appear more natural as to coloring, such as the flesh tones of human beings and the fur and hair of animals. We preferably use a repetition of colors in 45 this section because there is not the contrast between them that there would be if colder colors were used among them, so instead of making a few of these colors cover the space occupied by the middle section of the screen, 50 we get a softer and a more vari-colored effect by filling the space with quite a number.

In the upper portion of the screen, where little or no action takes place, long strips of 55 color are used which will be most appropriate for interior and exterior scenes and which will be in contrast to the colors in that portion of the screen where animation appears. For this purpose cold colors are 60 preferably used such as chrome yellow and blue, the edges of these colors being carefully blended and likewise being blended at their edges where they join the warmer colors of the intermediate section of the 65 screen. As before pointed out, these colors

are preferably applied in long strips or bands transversely of the screen in contrast with the shorter strips of color applied to the intermediate portion of the screen, for they better exhibit inanimate objects.

At the lower portion of the screen, where there is little or no action or movement of projected figures, a color scheme or effect is provided which will be in contrast with the softer, warmer colors above them and which will also be appropriate for objects most generally appearing in such portion of the screen, whether interior or exterior scenes are shown, and for this purpose we prefer to use other colors than those used in the intermediate and top portions of the screen, such as green, lilac, light red, blue and yellow. These colors are arranged more after the pattern of the colors in the intermediate section of the screen in the 85 sense that they are intermingled and run transversely across the screen for longer or shorter distances, each color along its edges being carefully blended into the color adjacent to it.

The employment at the top and bottom of the screen, where little action appears, of colors contrasting with those employed in the middle, animate section, assists materially in giving a variegated and pleasantly-tinted picture, for if the color scheme of the middle section covered the entire screen the picture projected upon such monotony of color would not appear with a vari-colored effect but more as a monotone.

The application of color to the screen may be accomplished in any suitable manner, the application being such, however, that the colors will appear in intermingled strips or patches, the strips running transversely the screen for longer or shorter distances, as previously explained. The application of the colors may be by painting directly upon the screen, water colors preferably being employed or any other suitable direct application. The colors may also be projected upon the screen as by projecting thereon colored rays of light from a suitable projecting machine or device. When the colors are projected a plate is employed which is colored according to the general scheme above outlined, the colors and blending being of course stronger than when applied directly to the screen in order to allow for the enlargement and consequent weakening of the colors by projection.

By the employment of a screen colored in accordance with our invention there is obtained not only a colored, lifelike picture, soft and pleasing to the eye and which can be used with any film, but the screen possesses other advantages, among which may be mentioned the fact that there is obtained a strong stereoscopic effect, which is a thing much to be desired in the art. A further

advantage resides in the fact that with those films where it is desired to project a dark, uncolored picture, the coloring of the screen has practically no effect, inasmuch as the 5 coloring affects essentially only those indoor and outdoor pictures where light, life and action prevail. The screen also is helpful in concealing imperfections in the film as where the film is scratched or otherwise defaced, and it also gives tone to pictures thrown from films of secondary character.

Having thus fully described our invention, we claim and desire to secure by Letters Patent of the United States:—

15 1. A moving-picture display screen having applied to it a color scheme sectional in character, the different sections each comprising a number of intermingled colors and the general color effect of adjacent sections 20 contrasting with one another.

2. A moving-picture display screen having applied to it a color scheme sectional in character, the different sections each comprising a number of intermingled, differently-colored tints of generally weak tone density, the general color effect of adjacent sections contrasting with one another and all adjacent tints being blended together along their meeting edges.

3. A moving-picture display screen having applied to it a color scheme sectional in character, the different sections each comprising a number of intermingled, differently-colored tints of generally weak tone density, the general color effect of adjacent 35 sections contrasting with one another, adjacent tints being blended together along their meeting edges and all the tints including the blending between them having substantially the same tone density. 40

4. A moving-picture display screen having applied to it a color scheme sectional in character, the different sections each comprising a number of intermingled, differently-colored tints of generally weak though 45 brilliant tone density, the intermediate section of the screen having applied to it soft colors, the outer sections of the screen at the top and bottom having applied to them cold colors, the general color effect of adjacent 50 sections contrasting with one another, adjacent tints being blended along their meeting edges and all the tints including the blending having substantially the same tone density.
